UNITED STATES PATENT OFFICE

118,983

DESIGN FOR A FLOOR LAMP

Serene G. Nelson, Frankfort, Mich.

Application November 9, 1939, Serial No. 88,164

Term of patent 7 years

To all whom it may concern:

Be it known that I, Serene G. Nelson, a citizen of the United States of America, residing at Frankfort, in the county of Benzie and State of Michigan, have invented a new, original, and ornamental Design for a Floor Lamp, of which the following is a specification, reference being had to the accompanying drawing, forming a part thereof.

In the drawing:

The dominant features of my design reside in the portions shown in solid lines.

I claim:

The ornamental design for a floor lamp, as shown and described.

SERENE G. NELSON.
